CORPORATION OF NEW YORK

MICROTOME KNIFE HOLDER

Application filed April 6, 1929. Serial No. 353,048.

This invention relates to microtomes of the type in which a specimen is reciprocated past a stationary knife to cut off successively thin microscopic sections of the specimen.

5 More particularly this invention relates to the knife holder which is used in a microtome of the character described.

It is often desirable, in the process of cutting sections with a microtome, to change 10 the cutting angle of the knife without otherwise altering the adjustment of the mechanism. This cannot be accomplished with prior devices, as far as we are aware, because any angular adjustment of the prior 15 art knife would change the distance between the knife edge and the specimen and thereby necessitate a re-adjustment of the knife holder on the base of the microtome.

It is an object of this invention to provide 20 an improved microtome knife holder which will permit adjustment of the cutting angle without varying the distance between the knife edge and the specimen. Another object is to provide gauging means on the 25 knife holder whereby the cutting edge of the knife can be properly positioned. These and other objects and advantages reside in certain novel features of arrangement, combination and construction of parts 30 as will hereinafter be more fully described and pointed out in the appended claims.

Referring to the drawings:

Fig. 1 shows an end elevation of our improved knife holder which is mounted on a 35 microtome of one type.

Fig. 2 shows a side elevation of our improved knife holder detached from the microtome.

Fig. 3 shows a longitudinal section of our 40 improved knife holder.

A preferred embodiment of our invention is illustrated in the drawings wherein our knife holder is indicated generally by H. The knife holder comprises a support 10 which is slidably mounted on the base B of a microtome M and adapted to be secured in adjusted position by means of the screw 11 and clamping member 12. The mechanism of the microtome M constitutes no part 45 of the present invention and so is not de-

scribed and shown in detail. The microtome has a specimen holder S which is vertically reciprocated and moved horizontally by small increments whereby successive sections are cut off of the specimen by the stationary knife when the wheel W is turned. It is obvious that our knife holder may be applied to any microtome of this general type and it is to be understood that our invention resides in the microtome knife 55 holder and not in the mechanism for reciprocating and advancing the specimen.

Movably mounted on the support 10 is the member 13 which can be secured in adjusted position by means of the clamping members 14 and 14' and the screws 15 and 15' co-operating with the nuts 16 and 16'. The upper part of member 13 is slotted as at 17 to receive the knife 18 which is removably secured by means of the clamping fingers 19 and 19' and screws 20 and 20'. The member 13 has a base or under side which is arcuately curved, as shown at 21 in Fig. 1, the center of curvature lying at a point O which is at the cutting edge of the knife 18. Suitable scale means 22 may be provided adjacent the arcuate base of member 13 to indicate the angular position of the knife 18.

When the knife 18 is removed for the purpose of sharpening it, the edge of the knife is ground away so that when the knife is replaced in the holder its cutting edge will no longer be located at the point O which is the center of curvature of the arcuate base 21 of member 13. Therefore, we provide gauging indicators 23 and 23' which are pivotally mounted on the member 13 adjacent the slot 17. As shown in Fig. 1, the indicators 23 are adapted to be swung upwardly to the dotted line position which is determined by the stop pins 24 and 24'. When the indicators are in this position their edges are at the center of curvature O and the knife 18 may be adjusted by means of screws 25 and 25' until the cutting edge is in line with the guiding edge of the indicators so that the cutting edge will again be located at the center of curvature O. The 100

indicators are swung downwardly when not in use.

From the foregoing it will be apparent that the cutting angle of knife 18 can be adjusted by merely loosening the nuts 16 and 16' and that such adjustment will not change the distance from the cutting edge to the specimen. Thus, while the microtome is being operated to cut a section of a given thickness, the cutting angle may be changed without altering the thickness of a single section because the cutting edge always maintains the same position relative to the specimen holder irrespective of the cutting angle. Various modifications can obviously be made without departing from the spirit of the invention as pointed out in the appended claims.

We claim:

- 20 1. A microtome comprising a specimen carrier adapted to be reciprocated, a knife holder carrying a knife adjacent to said carrier, said holder having a curved base, all points on the curve of said base being equidistant from the cutting edge of said knife.
- 30 2. A microtome comprising a specimen carrier, a knife holder, a knife in said holder, said carrier being adapted to be reciprocated past said knife, said holder having a curved base on which it is movably mounted whereby the knife may be angularly adjusted, the curved portion of the base defining an arc whose center of curvature coincides substantially with the cutting edge of said knife.
- 35 3. A microtome comprising a specimen carrier, a knife holder adjacent to said specimen carrier, a knife in said holder, said holder having an arcuately curved base whereby said knife may be angularly adjusted with respect to said specimen carrier, said curved base defining an arc of a circle whose center lies substantially on the cutting edge of said knife.
- 45 4. In a microtome, a knife holder having a knife adjustably secured therein, said holder having a curved base on which it is movably mounted whereby the knife may be angularly adjusted, said curved base defining an arc of a circle whose center lies above the holder and gauging means on said holder for determining the center of said circle.
- 50 5. In a microtome, the combination of a support, a knife holder adjustably mounted on said support, a knife in said holder, said holder having a base defining an arc of a circle whose center lies above said holder, gauging means carried by said holder for determining the center of said circle, means for adjusting the knife in said holder to position the cutting edge of the knife at the center of said circle.
